UNITED STATES PATENT OFFICE.

BARON HENRY SCOTFORD, OF ATLANTIC CITY, NEW JERSEY.

PAPER DOLL.

Application filed July 30, 1920. Serial No. 400,071.

To all whom it may concern:

Be it known that I, BARON HENRY SCOTFORD, a citizen of the United States of America, residing at Atlantic City, in the county of Atlantic and State of New Jersey, have invented a new and useful Improvement in Paper Dolls, of which the following is a specification.

My invention relates to paper dolls and particularly to cut-out paper dolls of distinctive appearance and fashioned in a novel manner and which are designed to be used either alone or with doll clothing fashioned and produced in a similar manner.

The objects of my invention are the production of an attractive doll and clothing therefor without the aid of printing, painting or any other of the arts or processes usually employed to impart to the doll and its clothing their distinctive appearance; and the production of a doll and doll-clothing from plain material solely by cutting from blanks parts of the material within the outlines of the doll and the doll clothing to form the desired pictorial representation or effect.

In the accompanying drawing, wherein are depicted examples of the various designs of dolls and doll garments in which my invention may be embodied,

Figure 1 is a front elevational view of a doll formed according to my invention, and Figures 2 and 3 are similar views of articles of doll clothing also fashioned according to my invention.

Both the doll and its clothing may be made of paper, light cardboard or other suitable material. The doll 1, shown in Fig. 1, is produced by cutting away surplus material from a blank to form the outline of the doll. When this is done by a person skilled in the art of portraying human features by the use of the scissors, accurate and life-like "scissors portraits" may be obtained.

The portrait is completed by a process which I term "snip-sketching", the features of the person whose likeness is being reproduced being applied to and bestowed upon the doll by cutting from the body of the doll at the appropriate selected points pieces of the material of varying shapes and sizes to form slits or openings 2 so formed and arranged as to give to the doll substantially the same appearance in general as if the design formed by the slits were printed or painted on the doll body.

The doll clothing is formed by this same process of "snip-sketching". The outline of a garment 3 is cut from a blank of any suitable material and of any desired color. The pattern or design of the garment is formed by means of slits or openings 2 produced by cutting or "snipping" material from the body of the garment in the same manner employed in forming the features and design of the doll hereinbefore described.

The doll garment thus produced and constructed may be made of cloth or fabric, paper, or other material, and may be used either alone or with a solid backing of the same or a different color. In order to present a more distinctive and more attractive garment, however, I prefer to paste or otherwise secure the doll garment to a sheet 5 of suitable material, preferably of a contrasting color with respect to the color of the garment.

For convenience in handling and for sale purposes a number of articles of doll clothing formed in the manner above described may be thus attached in spaced relation upon and to a single large sheet of paper or light cardboard, preferably somewhat flexible. In cutting out the garment so mounted, tabs are provided on the backing at suitable points on the edges of the garment, for example, at opposite edges of the top and sides, which tabs, 4, are adapted to be bent over the edges of a doll of the general type shown in Fig. 1 to fasten the garment thereto.

Instead of mounting the "snip sketch" garment directly upon the backing member 5, as shown in Fig. 3, the garment may be mounted as illustrated in Fig. 2, first on an intermediate backing member 6 of a color different from or contrasting with the color of the garment, and the backed garment then mounted upon the backing member 5 which may be of a color contrasting with the color of the intermediate backing and also preferably contrasting with the color of the dress or garment, although the same color of material may be used for the garment 3 and backing 5 with good effect.

The backing member 6 may extend slightly beyond the edge of the garment to form a distinctive border, and the backing member 5 may extend slightly beyond the edges of both the garment and the intermediate backing member.

In the drawings the tabs 4 are shown as formed on the backing member 5, but they

may, in cutting out the different parts, be formed on either the intermediate member 6 or the garment instead.

A garment fashioned and arranged in the manner and form described presents an attractive and novel appearance. The design of the clothing is effected by the slits or openings 2 and the provision of a material back of these apertures which is of a color preferably different from and in contrast with the color of the garment emphasizes the design, heightens the effect produced and materially increases the attractive appearance of the garment. The presence of a single or double border of contrasting colors along the edge of the garment, an example of which is depicted in Fig. 2, further heightens the artistic effect and furnishes an added element to the pleasing appearance of the garment.

A similar effect may be produced upon the appearance of the doll 1 by providing it with a backing of contrasting color in the same manner employed in connection with the garments shown in Figs. 2 and 3, the doll illustrated in Fig. 1 being shown with such a backing member 5. If desired, the backing member may be in the form

of a much larger sheet, taking the form of a panel upon which the doll may be mounted for sale purposes or in order to constitute a display card or a souvenir card.

I claim:

1. A cut-out figure doll having a body portion and a head portion, the body portion having apertures of varying size and shape in the material of which the doll is formed to depict the clothing of the doll, and apertures similarly formed in the head portion to depict distinctive physical features of the doll.

2. A doll garment having apertures of varying size and shape in the material of which the garment is formed, to represent the distinctive features of form and design of the garment, a backing for the garment of suitable material and possessing a color in contrast to the color of the garment, and a second backing member of suitable material and contrasting color upon which the garment and its first-mentioned backing are mounted, the backing members projecting beyond the edge of the garment to form a distinctive border for the garment and beyond one another.

BARON HENRY SCOTFORD.
